UNITED STATES PATENT OFFICE.

EDWARD F. CHAFFEE, OF NEW YORK, N. Y., ASSIGNOR TO OLIVER M. EDWARDS, OF SYRACUSE, NEW YORK.

TRAP-DOOR FOR RAILWAY-CARS AND SIMILAR STRUCTURES.

942,711.

Specification of Letters Patent. Patented Dec. 7, 1909.

Application filed June 17, 1909. Serial No. 502,697.

To all whom it may concern:

Be it known that I, EDWARD F. CHAFFEE, a citizen of the United States, residing in the borough of Brooklyn, county of Kings, city of New York, State of New York, have invented certain new and useful Improvements in Trap-Doors for Railway-Cars and Similar Structures, of which the following is a full, clear, and exact description, reference being had to the drawings accompanying the same.

This invention relates generally to the construction of metal trap doors for cars and similar structures, such for instance, as are used to cover and uncover the steps leading to and from the end platforms of passenger cars.

One of its objects is to provide a light, strong, easily constructed and readily cleaned metal door of this general class; another object is to construct such a door of a plurality of plates which are arranged in portions having separating means between such portions; another object is to so construct such a door with the parts so arranged that a portion of such parts form reinforcing means for another portion with the exposed surfaces of such portions substantially smooth; so that the under surface of the door is readily cleaned upon the opening of the door to prevent soiling the clothing of passengers in leaving or entering the car.

With these objects in view the invention consists in the construction, combination and arrangements of parts to be hereinafter more fully described and more particularly pointed out in the claims hereunto annexed and forming a part of this specification.

It has been found in use that trap doors such as are commonly used in passenger cars to cover the steps by which passengers enter and leave the cars not only have to be made very strong but it is very desirable that such doors be comparatively light in weight so that they can be easily and quickly opened and closed at stations. It is also desirable that such doors should occupy as little space as possible when opened and present substantially a smooth under surface which can be quickly and easily cleaned.

It has been found that trap doors when closed accumulate more or less dust and dirt on their under sides while the train is in motion and it is desirable to wipe off such

dirt and dust upon the opening of the same, so that the clothing of passengers will not be soiled when brought in contact therewith on entering or leaving the cars. This cleaning or wiping off the under surface of trap doors has to be done on the opening of the same and it is necessary that it be done quickly and effectively so as not to delay the trains at stations. In order to do this work quickly and with little expenditure of time and money the under surface of the door has to be substantially smooth and without any protuberances or projections to interfere with the wiping or cleaning operation. These trap doors like the vestibule platform or floors, where they are used, commonly receive a covering usually in the form of a tiling, with a surface adapted to prevent those using the cars from slipping thereon. The upper surfaces of the doors are usually substantially flush with or in line with the rest of the platforms in which they are used.

Figure 1 shows in plan view a door and a section of a car or vestibule platform illustrating generally the door when in the closed position, a portion of the upper covering or tiling being broken away. Fig. 2 shows in cross section that which is seen on line 2-2 of Fig. 1. Fig. 3 shows in cross section and on an enlarged scale that which is seen at the left of Fig. 2. Fig. 4 shows in cross section on line 4-4 of Fig. 1, which is arranged at right angles to the section shown in Fig. 2. Fig. 5 shows in plan view a modified form of arrangement of parts wherein a plurality of plates or parts may be used for forming a substantially smooth surface for one side of the door. Fig. 6 shows a plan view of a modified construction of door, and Fig. 7 shows in section on line 7-7 of Fig. 6 that which is there shown.

Like letters of reference, wherever they occur, indicate corresponding parts of the several figures of the drawings.

In Figs. 1 to 4, inclusive, A represents the car or vestibule platform in which the door B is hung so as to be opened and closed by means of any suitable form of hinge desired. As shown a well known form of hinge means connects the door to the platform so that it may be readily opened and closed. The door B as seen is preferably made up of a top plate of metal C and an under plate D having at three of its edges

bent up angle pieces b , b' and b'' , adapted to receive and hold the plates C and D, such plates being secured together by rivets as shown, or in any other desired manner which 5 the constructor sees fit to use. These bent up angle parts are preferably made in U shape and preferably receive the edges of both the plates C and D on three sides of the door. The hinge portion E is preferably 10 made to extend substantially across the rear edge of the door and also to receive the rear edges of the plates C and D as shown in Fig. 2, the free edges of the hinge portion E preferably being brought into position to 15 receive the plates and hold them in contact with one another and such hinge portion. These bent up angle pieces b , b' and b'' , form binding means for the front and side edges of the door and the hinge portion E forms 20 a binding means for the other edge of the door which binding means form a frame which acts to stiffen or reinforce the edge portions of the door where the same is supported in the opening in the platform which 25 the door is designed to close. These binding means are preferably made with suitably beveled edge portions in conformity with that which is set forth in Letters Patent No. 30 847,559, dated March 19, 1907 for trap door bindings, so that the door may be readily opened without undue binding in the opening of the platform and also receive and aid in holding the extreme outer edges of the tiling in place, as shown or otherwise as is 35 desired. Any form of tiling or tread surface, as F, may be used on the upper surface of the plate C that is desired.

As shown, the separating means G, preferably made in a single piece, is interposed 40 between the plates C and D and necessarily forms reinforcing means when the plates are secured together with such means arranged between them. The plates C, D and such means are preferably secured together as 45 shown, or otherwise as the constructor desires, as for instance, as shown in Figs. 6 and 7, where such means are secured to only one plate or portion, but such means is interposed between the two plates or two portions of plates to reinforce and strengthen 50 the door. When such means and plates are secured together a compound truss is formed, that is, a structure which embodies the principle of a truss in two directions, one 55 at right angles to the other, as seen in Figs. 2 and 4. A door constructed on this principle is exceedingly strong and comparatively light as the plates composing it are of less thickness, when taken together, than a single 60 plate would be if the reinforcing ribs are formed in such plate. As shown, the plate D is much thinner than plate C and the means interposed between them is necessarily of little weight as all strains thereon 65 are of a compression nature, or such as tend

to crush such means. These reinforcing and separating means may be of any desired form, construction and arrangement, relatively to the plates the constructor sees fit to employ, so long as they are adapted to do 70 the work they do in the embodiment of the invention herein illustrated. As shown, the plate D forms a substantially smooth surface for the under side of the door which is adapted to be readily wiped off and cleaned 75 by the person in charge of the car upon the opening of the same for the ingress or egress of passengers.

Instead of constructing the door out of two plates as shown in preceding figures 80 they may be made with a greater number, as the constructor desires. If desired, the under side of the door for instance may be made up of a plurality of plates as shown in Fig. 5 and yet have the same reinforcing 85 or compound truss action present as is the case when only one plate, as D, is employed. In the construction seen in Fig. 5 there is a plate H for the top part of the door and a plate I for a portion of the under side of 90 the door which extend from the hinge edge of the door to the front edge thereof. This plate H is preferably of about the size of the door and the plate I is preferably of about the width of the reinforcing or separating means G. There is also a plate J 95 forming another portion of the under side of the door which extends from one side edge to the other side edge thereof at right angles to the plate I and it is also preferably of about the width of the separating means shown. Plates I and J are shown as of substantially the width of the reinforcing means G seen in Figs. 1 to 4. There are no special dies or machines required for giving the necessary bends or shape to these plates I and J, in order to have the ends thereof readily contact with the edges of the plate H and receive hinging and binding means similar to what is shown in preceding figures. When 100 the plates I, J, H and the reinforcing or separating means G are secured together after the manner shown in Figs. 1 to 4, there is the same truss action in this construction as there is in the construction seen in preceding figures. The reinforcing means G necessarily hold the plates I and J some distance away from the plate H and such plates I and J form a substantially smooth under surface for the door which is quickly and conveniently cleaned on the opening of the same to prevent the clothing of passengers being soiled in entering or leaving the car. The spaces at the corners of the under side of the plate H not covered by the plates I 115 and J are some little distance from the outer surfaces of such plates and consequently the clothing of those entering and leaving the car will naturally not be brought in contact with these portions of the plate H and be 120 125 130

soiled by any dirt that may be on such plate. If desired, these spaces may be filled in any known manner.

The reinforcing means, as G, which is interposed between the upper and under plates of the door may be of any desired form or construction, so long as the plates are properly separated and embody the principle of a truss thereby reinforcing or strengthening the door. Instead of the specific reinforcing means G seen in preceding figures any desired form and arrangement may be employed, as for instance such as is seen in Figs. 6 and 7. Also instead of the arrangement of the plates to form the upper and under surfaces of the door seen in preceding figures, the arrangement may be that seen in Figs. 6 and 7, or any other that is desired.

The door illustrated in Figs. 6 and 7 is somewhat narrower in width than it is lengthwise or from the hinge edge to the front edge thereof and as shown it is made up of two plates of substantially the same width and length, the under plate D² being much thinner than the upper one C². The means G² interposed between these plates C² and D² reinforces and strengthens the door and separates the two plates one from the other and the door embodies said truss principle.

These means are shown as being bent up out of sheet metal into angular form, as is clearly seen in Fig. 7 and the same are preferably secured to the plate C² by rivets, as shown, or in any other suitable manner. These reinforcing means consist, as shown, of two parts, each of which extends substantially across the width of the door or from side to side thereof and such parts are some little distance apart so as to separate the plates and reinforce the door as shown.

The plates C² and D² are only secured together at the front and rear edges of the door, the plates at the side edges of the door being separated as shown in Fig. 7. Suitable binding or framing means may be employed to bind and form a frame for the front and side edges of the door, such for instance as is seen in preceding figures, or otherwise as desired, such binding or framing means preferably being arranged so as to receive the extreme front and rear edges of both of the plates C² and D² as shown.

Any desired form of hinging means may be employed as for instance the form shown in preceding figures or any other that the constructor sees fit to employ.

In each of the embodiments herein shown the means which reinforce or strengthen the central portions of the door are arranged so as to act thereon between the points where the door is supported in the platform. In the embodiments herein shown the under surface of the door is substantially smooth and consequently readily and quickly wiped off or cleaned upon the opening of the same.

What I have herein shown and described will naturally suggest to others skilled in this art other embodiments of this invention and also modifications in the construction and arrangements of parts wherein substantially the same results may be accomplished by combinations of elements or devices having essentially the same mode of operation as the combinations have that are particularly pointed out in the claims hereunto annexed, hence I do not wish to limit my invention to the specific forms and arrangements herein shown and described, but desire to include all forms and arrangements which embody the spirit of my invention and which have substantially the same mode of operation as do the specific parts and arrangements herein set forth.

What I desire to claim as new is:—

1. A platform trap door comprising a plurality of plates arranged in two portions and adapted to be secured together and to hinge means and form substantially a flat surface for one side of the door and substantially a smooth surface for the other side, which portions are secured together with means arranged between them in position to reinforce and stiffen the central portions of the door and hinging means secured to the plurality of plates for hinging the door in the platform.

2. A platform trap door comprising a plurality of plates arranged in two portions, one portion of which forms a substantially flat surface and another portion forms substantially a smooth surface, such surfaces being opposite one another and being secured together with means arranged between them in position to reinforce and stiffen the central portions of the door.

3. A platform trap door comprising a plurality of plates arranged in two portions which are secured together and to hinging means and form a substantially flat surface for one side of the door and substantially a smooth surface for the under side of the door, such portions being secured together in such manner that the two portions are nearer to each other near the edge of the door than they are toward the center thereof with means arranged between such portions in position to reinforce and stiffen the central portions of the door.

4. A platform trap door comprising a plurality of plates arranged in two portions, one of which forms substantially a flat surface to receive the tiling for the door and the other forms substantially a smooth under surface of the door, which portions are secured together with means arranged between them in position for such means and a portion of such plates to reinforce and stiffen the central portions of the door and U shaped binding means secured to the side and front edges of the door.

5. In a platform trap door the combination, substantially as set forth, of a plurality of plates, means adapted to separate one portion of such plates from another portion 5 and thereby reinforce the central portions of the door, hinge portions adapted to hinge the door in the platform, and means adapted to secure the plates together adjacent to the edges of the door with separating means 10 between the two portions of said plates.
6. In a platform trap door the combination, substantially as set forth, of a plurality of plates, one portion of which is thinner than another, means adapted to separate one portion from the other, and thereby reinforce the door, one of which portions is held substantially flat, hinge portions adapted for hinging the door in the platform, and means adapted to secure the two 15 portions of the plates together adjacent to the edges thereof with the reinforcing means arranged relatively to the door to stiffen and strengthen the same.
7. In a platform trap door the combination, substantially as set forth, of a plurality of plates, one portion of which is thinner than another, reinforcing means adapted to separate one portion from another with one of such portions substantially flat and the other arranged at acute angles to the flat portion, hinge portions adapted for hinging the door in the platform, and means adapted for securing the portions together with the reinforcing means arranged relatively 20 to the door to stiffen and strengthen the same.
8. In a platform trap door the combination, substantially as set forth, of two plates, reinforcing means adapted to separate the central portions thereof one of which is substantially flat, hinge portions adapted to hinge the door in the platform, means adapted to secure the plates together adjacent to the edges thereof with the reinforcing means 25 arranged to stiffen and strengthen the door.
9. In a platform trap door the combination, substantially as set forth, of a plurality of plates, one portion of which is adapted to receive the tiling for the door and the other is adapted to form a substantially smooth under surface for the door, reinforcing means adapted to separate one portion from another portion, hinge portions adapted for hinging the door in the platform, binding 30 means for the front and side edges of the door, and means adapted to secure the binding means and plates together and hold them with the reinforcing means arranged relatively to the plates for stiffening and 35 strengthening the same.
10. In a platform trap door the combination, substantially as set forth, of a plurality of plates, reinforcing means adapted to separate one portion from another portion which portions are so arranged relatively 40
- thereto that such reinforcing means tends to hold one portion of the plates against bending when the plates are secured together, and means adapted to secure the plates together with the reinforcing means arranged 70 in position to stiffen and strengthen the door.
11. In a platform trap door the combination, substantially as set forth, of a plurality of plates, means adapted to separate one portion from another portion which portions are so arranged that such separating means and one portion of the plates, when the plates are secured together, reinforces and strengthens the other portion, U shaped 75 binding means for the front and side edges of the door, and means adapted to secure the plates and binding means together with the separating means between such portions, whereby the door is reinforced and strengthened 80 at its central and edge portions.
12. In a platform trap door the combination, substantially as set forth, of a plurality of plates arranged in two portions, a single piece of material adapted to separate the central portions of the plurality of plates, means adapted to secure the plates together with such single piece between them, and hinging means adapted to hinge the door in the platform, whereby the door is reinforced 85 and strengthened.
13. In a platform trap door the combination, substantially as set forth, of a plurality of plates, one portion of which is adapted to form one member of a compound truss and the other is adapted to form another member 90 of such truss, means arranged between the two members and adapted to separate them, one from the other, and securing means adapted to secure together such members 95 and the means which separate them, whereby the plates are held against bending in two directions, one at an angle to the other.
14. In a platform trap door the combination, substantially as set forth, of a plurality of plates, one portion of which is adapted to form a flat member of a compound truss and the other portion is adapted to form a bent member of such truss, means arranged between the two members and adapted to separate them, one from the other, and securing means adapted to secure together such members 100 and means arranged between them, whereby the plates are held against bending in two directions, one at an angle to the other.
15. In a platform trap door the combination, substantially as set forth, of a plurality of plates, one portion of which is adapted to form one member of a compound truss and the other portion is adapted to form another member having a substantially smooth surface, means arranged between the members 105 and adapted to separate them, one from the other, and securing means adapted to secure 110
- 120
- 125
- 130

together such members and means arranged between them, whereby the plates are held against bending in two directions, one at an angle to the other.

- 5 16. In a platform trap door the combination, substantially as set forth, of a plurality of plates a portion of which form a flat surface adapted to serve as one side of the door and another adapted to form a smooth surface for the other side of the door, means arranged between the central portions of the plurality of plates, and securing means adapted to secure together the plates and the means arranged between them, whereby the 10 plates are held and reinforced against bending.

17. In a platform trap door the combination, substantially as set forth, of a plurality of plates, one portion of which is adapted to 20 form a flat surface for one side of the door and another portion is bent to form a substantially smooth surface for the other side of the door, means adapted to be interposed between the two portions of the plate for reinforcing and stiffening the door, and securing means adapted to secure the plurality of plates and interposed means together, whereby the plates are held and reinforced against bending.

- 30 18. In a platform trap door the combination, substantially as set forth, of a plurality of plates, one portion of which is adapted to form a flat surface for one side of the door and another portion is adapted to form a substantially smooth surface for the other side of the door, means adapted to be interposed between the two portions of plates for reinforcing and stiffening the door, securing means adapted to secure the two portions of 35 the plates together, binding means secured to the front and side edges of the door and adapted to stiffen the same, and hinging means adapted to hinge the door to the platform, whereby both the central and edge 40 portions of the door are reinforced and stiffened against bending.

19. In a platform trap door the combination, substantially as set forth, of a plurality of plates one portion of which is adapted to 50 form a flat surface for one side of the door and another portion is adapted to form a substantially smooth surface for the other side of such door, reinforcing means adapted to be interposed between the two portions of 55 the plates and separate the same, binding means adapted to receive and hold the front and side edges of the two portions of the plate and be secured thereto, means adapted to secure the plates and binding means together with the reinforcing means interposed between the plates, whereby the plates are held and reinforced against bending.

- 60 20. In a platform trap door the combination, substantially as set forth, of a plurality of plates one portion of which is adapted to

form one side of the door and another portion is adapted to form a substantially smooth surface for the other side of the door, reinforcing means adapted to be interposed between the two portions of the plates, hinge 70 means adapted to hinge the door in the platform and strengthen the rear edge of such door, binding means adapted to secure the plates together at their front and side edges and securing means adapted to secure the 75 binding means and plates together, whereby both the central and edge portions of the door are reinforced and stiffened.

21. In a platform trap door the combination, substantially as set forth, of a plurality of plates, means adapted to be interposed between the plates to separate one portion from another, which portions are so arranged relatively to the interposed means that such portions are held and reinforced 80 against bending when such portions and means are secured together, U shaped binding means adapted to receive the side and front edges of the plates and hold and stiffen the same, and means adapted to secure together the two portions, the interposed means and the binding means, whereby both the central and edge portions of the 85 door are reinforced and stiffened.

22. In a platform trap door the combination, substantially as set forth, of a plurality of plates, means adapted to be interposed between the plates to separate one portion from another, which portions are so arranged relatively to the interposed means 90 that such portions are held and reinforced against bending, when such portions and means are secured together, binding means adapted to extend above the top plate and receive the front and side edges of the tiling, 100 means adapted to secure the binding means and plates together with the interposed means between the plates, whereby both the central and edge portions of the plates are 105 held and reinforced against bending.

23. In a platform trap door the combination substantially as set forth, of two plates, means adapted to be interposed between the plates and so arranged relatively thereto that such means separates one plate 115 from the other, when the two are secured together, and means adapted to secure the plates and interposed means together, whereby the plates are reinforced and stiffened against bending.

24. In a platform trap door the combination, substantially as set forth of two plates, means adapted to be interposed between the plates and so arranged relatively thereto that such means separate one plate from the 125 other, when the two are secured together, means adapted to secure the plates and interposed means together, a hinge portion adapted for hinging the door in the platform which portion extends substantially 130

across and receives the rear portion of the plates and means adapted to secure the hinge portion and plates together, whereby the central portion and rear edge portion of the plates are reinforced and stiffened against bending.

25. In a platform trap door the combination, substantially as set forth, of two plates, means adapted to be interposed between the plates and so arranged relatively thereto that such means separate one plate from the other, when the two are secured together, a hinge portion adapted to hinge the door to the platform and extend substantially across the door and receive the rear portions of the plates, binding means adapted to bind and stiffen the side and front edges of the door, and means adapted to secure the binding means, the hinge portion and plates together, whereby the plates are reinforced and strengthened at the central and edge portions thereof.

26. In a platform trap door the combination, substantially as set forth of two plates, one of which is adapted to form one side of the door and the other is bent and thereby adapted to contact with the other plate and form a substantially smooth surface for that

side of the door, means adapted to be interposed between the central portions of the plates and so arranged relatively thereto that such means separate the central portion of one plate from that of the other, when the two are secured together, and means adapted to secure the plates and interposed means together, whereby both the central and edge portions of the plates are held and reinforced against bending.

27. In a platform trap door the combination, substantially as set forth, of a plurality of plates, means adapted to be interposed between the plates and so arranged relatively thereto that such means separates one portion of the plates from another portion, binding means adapted to be secured to the edges of the door and form a frame therefor, and securing means adapted to secure the plates, the interposed means and the binding means together, whereby the central and edge portions of the door are reinforced and strengthened against bending.

EDWARD F. CHAFFEE.
